UNITED STATES PATENT OFFICE.

ERICH HINRICHSEN, OF HAMBURG, GERMANY, ASSIGNOR TO THE FIRM: AUGUST STICH, OF HAMBURG-WILHELMSBURG, GERMANY.

APPARATUS FOR RELEASING SHIPS' LIFEBOATS.

Application filed November 14, 1928, Serial No. 319,365, and in Germany September 21, 1928.

The prompt and reliable releasing of boat-hoisting hooks from which loaded ships' life boats hang is of the utmost importance in moments of danger. The present invention relates to an appliance with which, by a single manual operation, a ship's life boat hanging in its tackle can be released without special expenditure of force, either when the boat is still suspended above the water or when it is already partially or completely floating upon the water.

The invention is illustrated by way of example in the accompanying drawings in which

15 Figure 1 shows one of the hood devices in side elevation, partly in section,

Figure 2 shows a side elevation of a ship's boat with a pair of the hook devices fitted to it, and

20 Figure 3 shows a corresponding plan view.

The boat-hoisting hook *a* is rotatable about a bolt *b*. The latter is guided in forks *c* and *c'*, which are connected with the stem or stern part and with the keel of the boat. A rear-

25 ward extension of the hook *a* rests upon a rotatable bolt *d*, formed with a notch through which, when the bolt *d* is suitably rotated, the hook can push its way in a downward direction in consequence of the pull exerted at the 30 point of suspension by the weight of the boat, so that the suspension cable slips out of the hook *a*.

The rotating of the bolt *d* is effected by means of a lever *e*, which is provided with a 35 counterweight and connected by a wire rope *f* with a similar lever *e'* which is located at the opposite end of the boat and connected with a second similarly shaped boat-hoisting hook *a'*. Upon the wire rope *f* is mounted at a 40 suitable position a handle or lever *g* for actuating the device.

Since only a force sufficient to overcome the friction of the bolt *d* is required, the expenditure of force necessary for actuating the device is quite inconsiderable and is independent of the magnitude of the load resting upon the two hoisting hooks *a* and *a'*.

The apparatus can obviously be used not only for life boats but also for other articles hanging from suspension cables or chains.

What I claim is:—

1. Apparatus for releasing life boats and other suspended articles from their suspension means, such as cables or chains, comprising stationary supporting means, a suspension hook rotatably mounted in the said supporting means, a member rotatably mounted in the supporting means near the hook in such a position that some part of the hook at a distance from its axis of rotation can engage 55 with the rotatably mounted member, the said rotatably mounted member being formed with a notch through which the engaged part of the hook can slip when the rotatable member is rotated into a particular position, thereby 60 enabling the suspension means to become disengaged from the hook, means such as a weighted lever secured to the said rotatably mounted member and tending to rotate it in one direction out of the position in which 65 the hook can slip through the notch, and means for rotating the rotatably mounted member in the opposite direction at will for 70 releasing purposes.

2. Apparatus for releasing life boats and other suspended articles from their suspension means, such as cables or chains, comprising stationary supporting means, two similarly shaped suspension hooks rotatably mounted in the said supporting means, an extension on each of the said suspension hooks, a bolt rotatably mounted in the said supporting means near each hook in such a position that the extremity of the hook extension can rest on the bolt, the said bolt being formed with 80 a notch through which the extremity of the hook extension can slip when the bolt is rotated into a particular position, thereby enabling the suspension means to slip off the hooks, means such as weighted levers secured 85 to the said bolts and tending to rotate them in one direction out of the position in which the hook extensions can slip through the notches, and means for rotating the bolts in the opposite direction at will for releasing 90 purposes.

In testimony whereof I have signed my name to this specification.

ERICH HINRICHSEN.
